UNITED STATES PATENT OFFICE.

JOHN H. JANN, OF CHICAGO, ILLINOIS.

WALL-SAFE.

1,087,378.

Specification of Letters Patent. Patented Feb. 17, 1914.

Application filed April 4, 1912. Serial No. 688,548.

To all whom it may concern:

Be it known that I, JOHN H. JANN, a citizen of the United States, residing at Chicago, in the county of Cook and State of Illinois, have invented certain new and useful Improvements in Wall-Safes, as set forth in the following specification.

A principal object of my invention is to provide a wall safe or the like wherein the edges of the adjoining walls will be firmly and permanently secured together without the use of bolts, rivets or fastening means other than the interlocking connection between the edges of the said walls.

15 A further aim of my invention is to provide a wall safe or the like wherein the edges of adjoining walls will be firmly and permanently interlocked and which, by virtue of the peculiar form of the interlocking connection between the said edges will aid materially in retaining the wall safe in the wall by engaging the plaster or other material forming the said wall.

25 A further aim of my invention is to provide a wall safe which may be cheaply manufactured, and which will necessitate in its construction a minimum amount of material to accomplish the various other aims and objects of my invention.

30 Additional objects will be apparent as the invention is better understood from the following description which, taken in connection with the accompanying drawings, illustrates one preferred embodiment thereof.

35 On the drawings:—Figure 1 is a perspective view of a wall safe constructed in pursuance of my invention; Fig. 2 is an enlarged vertical sectional view taken in the plane 2—2 of Fig. 1 showing the means of connecting an end wall to the top and bottom walls; Fig. 3 is an enlarged vertical sectional view taken in the plane 3—3 of Fig. 1 disclosing the interlocking connection between the top and bottom walls and the 40 front wall, and Fig. 4 is an enlarged horizontal sectional view taken in the plane 4—4 of Fig. 1 showing the interlocking connection between the end and front walls.

45 In the preferred embodiment of my invention shown in the drawings I provide a wall safe generally designated as 10 which is formed of a plurality of flat rectangular walls interlocked at adjoining edges as hereinafter described, although it will be obvious that the shape of the box may be varied within wide limits with slight modifications

of the connections between said walls which may be readily made by those skilled in the art.

The box 10 is composed primarily of front and rear walls 11, top and bottom walls 12 and end walls 13. The front wall 10 is provided with a wall safe door 14 of any preferred style. Upon the top wall 12 to aid in supporting the box in the wall of a building I provide an anchor-receiving member 15 secured to the said top wall as at 16 by inserting through apertures provided in the said wall inwardly extending lips 17 and bending the said lips against the inner surface of the said wall. The outer edges of the front and rear walls are bent outwardly to form a flange 18 extending along the four sides of the said walls. These flanges are preferably at right angles to the plane of the said wall, although it will be obvious that they may be disposed at a greater or less angle thereto as may be desired. The top and bottom walls 12 and the end walls 13 are offset adjacent the front and rear walls 11 to form the shoulders 19, and are of proper dimension to permit the said front and rear walls to seat against these shoulders. Beyond these shoulders the edges 21 of the walls are bent to embrace the flanges 18 to 45 firmly hold the said front and rear walls against the shoulders 19 of the said top, bottom and end walls. The top and bottom edges of the end walls are offset to form the shoulders 22 and the end edges 23 of the top and bottom walls 12 extend beyond the inner faces of the said end walls and are seated upon the shoulders 22 of the said end walls, where they are retained in position by the edges 24 of the said end walls, which 50 for this purpose are bent back over the ends 23 of the top and bottom walls as is disclosed in Fig. 2.

Inasmuch as the front wall, or the wall carrying the door of the safe, is the wall most frequently subjected to attack by burglars desiring to break into the safe, I provide the reinforcing plate 25 upon the said wall which may be secured thereto in any suitable manner, and which may be omitted 55 if it is desired without sacrificing any of the advantages of my invention.

It will be manifest that in providing the top, bottom and end walls with the shoulders 19, and the front and rear walls with 60 the outwardly disposed flanges 18 that when the said front and rear walls are seated

against the said shoulders and the said flanges embraced by the edges of the top, bottom and end walls that a secure and permanent union is provided between the said 5 top, bottom and end walls and the front and rear walls, and that the ends of the said top and bottom walls will be firmly secured to the end walls by the shoulders 22 and the turned back edges 23 of the end walls. It 10 is thus obvious that a secure union is established between all the walls without the use of bolts, rivets and the like.

It will be manifest that the front and rear walls extend outwardly beyond the edges of 15 the top, bottom and end walls when the wall safe is constructed in accordance with my invention and that the end walls are spaced inwardly of the adjacent edges of the top, bottom, front and back walls, thereby disposing the interlocking edges and the shoulders against which the edges of the various 20 walls rest outwardly from the body of the box in position to be engaged by the material forming the wall in which the safe is embedded to provide an anchorage and prevent removal of the safe.

It will be apparent that numerous changes 25 may be made in the construction and form of the walls without departing from the spirit and scope of my invention or sacrificing any of its benefits, the form hereinbefore disclosed being merely one preferred embodiment thereof.

I claim:—

- 35 1. A wall safe comprising a plurality of walls, a pair of adjacent edges of one of said walls being bent outwardly to form adjoining flanges, the adjoining edges of the second wall being offset to form a shoulder 40 against which said first-mentioned wall is positioned and bent to embrace one of said flanges, the edges of a third wall adjacent said first and second walls being bent outwardly to 45 form shoulders against which both said first and second walls are positioned and over the adjacent edges of said walls to bind the three walls together and to provide means for retaining the box in position in the wall of a building.
- 50 2. A wall safe comprising a plurality of rectangular walls, two adjacent edges of a single wall being bent outwardly to form

flanges abutting at a corner of said wall, the edges of two intersecting walls behind the said first-mentioned wall being offset 55 to form shoulders against which said wall is positioned, and bent to embrace said flanges, said shoulders abutting behind the said corner of said first wall, and an edge of one of said intersecting walls being offset behind 60 the other wall to form a shoulder extending to said corner against which the edge of the other intersecting wall is positioned and bent over said last-mentioned edge, to bind the three walls together and to provide 65 means for retaining the box in position in the wall of the building.

3. A wall safe formed of a plurality of interlocking sheet metal walls, the interlocking connection of two opposite walls with 70 the walls connecting the same being disposed outwardly substantially at right angles to the plane of the said opposite walls, and the interlocking connection of a pair of opposite connecting walls with the first- 75 mentioned walls and with the remaining walls being disposed outwardly substantially at right angles to the plane of the said opposite connecting walls, to bind the three walls together and to provide means for retaining 80 the box in position in the wall of the building.

4. A wall safe formed of a plurality of interlocking sheet metal walls, the interlocking connection of two opposite walls 85 with the walls connecting the same being disposed outwardly substantially at right angles to the plane of the said opposite walls, and the interlocking connection of a pair of opposite connecting walls with the 90 first-mentioned walls and the remaining walls being disposed outwardly substantially at right angles to the plane of the said opposite connecting walls, the main portions of said opposite connecting walls being 95 spaced inwardly of the adjacent edges of all the remaining walls, to bind the three walls together and to provide means for retaining the box in position in the wall of the building.

JOHN H. JANN.
